UNITED STATES PATENT OFFICE.

JOHN H. HUMES, OF ST. LOUIS, MISSOURI.

DESIGN FOR A PUNCH.

SPECIFICATION forming part of Design No. 28,740, dated May 31, 1898.

Application filed October 22, 1897. Serial No. 656,106. Term of patent 7 years.

To all whom it may concern:

Be it known that I, JOHN H. HUMES, a citizen of the United States, residing at St. Louis, State of Missouri, have invented and produced a new and original Design for Punches for Forming Belt-Fasteners, of which the following is a specification, reference being had to the accompanying drawing, showing a part thereof.

10 The drawing is a perspective view of my new design.

As shown in the accompanying drawing, the body 1 is provided with cutting edges, all of which are on a plane with one another and 15 form the leading feature of my design.

Referring to the drawing, 2 and 3 represent two blades or walls on a line with one another, and 4 and 5 two similar blades or walls arranged at right angles to the first-named 20 walls and form a continuation of the same,

a plane surface 6 separating the walls 4 and 5 and located below the edges of said last-named walls. The walls 7 and 8 are arranged similar to the walls 2 and 3 and form a continuation of the walls 4 and 5. Forming 25 a continuation of the wall 8 and projecting at right angles from the same is an additional wall or wing 9.

Having described my invention, what I claim as new, and desire to secure by Letters 30 Patent, is—

The design for a punch, substantially as herein shown and described.

In testimony whereof I affix my signature in presence of two witnesses.

JOHN H. HUMES.
